Fig. 10

stituting the rearward and upper portion of the bleacher;

The common features of the two illustrated embodiments of my new design consist primarily in the shape of the upright members upon which the horizontal seat portions and walkways are mounted.

This application is a continuation-in-part of application Ser. No. D. 9,822 filed Dec. 18, 1967 and now Patent No. D. 213,871.

I claim:

The ornamental design for a bleacher, substantially as shown and described.
